UNITED STATES PATENT OFFICE.

ELISA M. SOUVIELLE, OF JACKSONVILLE, FLORIDA.

WINDMILL.

1,246,484.

Specification of Letters Patent.

Patented Nov. 13, 1917.

Application filed December 30, 1916. Serial No. 139,828.

To all whom it may concern:

Be it known that I, ELISA M. SOUVIELLE, a citizen of the United States, and resident of Jacksonville, county of Duval, State of Florida, have invented certain new and useful Improvements in Windmills, of which the following is a specification.

This invention relates to motors operated by the wind and its purpose is to simplify the construction and produce a motor which will be more efficient in operation than any heretofore in use. It embodies a rotary member including vanes of the particular construction adapted to secure the greatest amount of energy from the wind, together with a fly wheel to give steadiness to the operation. The novel features of the invention will be apparent from the following description taken in connection with the drawings.

In the drawings,

Figure 1 is a perspective view of a construction embodying my invention;

Fig. 2 is a view of the impeller separate from the support blades;

Fig. 3 is a sectional view showing a slightly modified way of making the vanes.

As shown in the drawings, my device is mounted in a frame having the four posts 1 connected by cross pieces 2, 3, 4 and 5 at the top, together with suitable bracing members. Below the top there is a secondary frame made up of the connecting members 6, 7, 8 and 9 with suitable cross braces for strengthening the frame. At the top there is a cross piece 10, which as hereafter explained carries the bearing for the upper end of the rotary member of my device and below that member there is a cross piece 11 which carries the lower bearing. It will be understood that my invention is not limited to the use of this particular form of frame for supporting the rotary motor and that any other suitable form of support may be used.

The main element of my invention resides in the rotary impeller which, as shown in Fig. 1, is provided with a shaft 12 at the top and a bearing 13 at the bottom. Radiating from the axis in line with the bearing 13 and shaft 12 are the vanes or blades 14, 15, 16 and 17. These blades or vanes are preferably made of sheet metal and are curved in cross section so as to be turned by the wind. The two opposite blades 14 and 16 are cut away at the center providing openings 18 and 19 which permit the passage of air

through them. The vanes, furthermore, are substantially V-shaped in form with the top of the V at the axis, whereby they have an upper edge extending downward at an angle 60 to a pointed outer margin. The material of the vane is bent over at the top to form a flange 20 which extends at an angle up to a point near the axis. The purpose of this flange is to catch the air striking the vane so 65 that there will be an upward pressure against the under side of this flange tending to raise the rotary member as a whole, thus relieving the weight on the bearings. These flanges 20 are formed preferably by cutting 70 the sheet metal material of the vane and bending the parts so as to make overlapping sections. This is necessary owing to the curvature of the blades.

Below the vanes 14, 15, 16 and 17 I place 75 a heavy ring 21, this ring being substantially below the outer points of the vanes. It is connected to the shaft at the axis of the rotary member at the bottom by any suitable means, such as the rods 22. It is also connected to the outer pointed ends of the vanes by means of the tension wires 23 which extend at an angle from the end of the vane to the weighted wheel constituting the fly wheel. These tension wires serve to transmit the power applied to the vanes by the wind to the weighted wheel in order to turn it.

In some instances the shaft on which the vanes are mounted may be made to extend 90 entirely from the top to the bottom and in that case I preferably make one of the vanes of two sheets of metal fitting against the opposite sides of the shaft, as shown in Fig. 3, where 24 represents the shaft and 25, 26 represent the two sections making up the two opposite vanes.

It will be observed that the construction above indicated will not only effectively utilize the force of the wind reducing the 100 friction very much but that it may be made easily and without much expense.

Having described the invention what is claimed and desired to be secured by Letters-Patent is,

1. The combination in a wind motor of radiating sheet metal vanes curved in horizontal section and having upper edges inclined downward from the axis, the upper inclined edges being cross cut and bent over in overlapping sections to form a flange along the top, a heavy ring below said vanes concen-

tric with the axis of rotation and inclined connections from the ends of said vanes to said ring.

2. The combination in a wind motor of four V-shaped sheet metal vanes, two of which have openings therethrough in their central portions next to the axis and all of which are curved in cross section and each having upper inclined edges being cross cut 10 and bent over in overlapping sections to form a flange along the top, a heavy ring below said vanes concentric with the axis of rotation and inclined connections from the ends of said vanes to said ring.

3. A wind motor comprising rotatable radiating V-shaped vanes, the top of the V in each case being at the axis of rotation and the edge of each vane being bent to form a flange along the top and each vane being curved in horizontal section, a heavy ring 20 below said vanes and rotatable therewith, and connecting means extending from the outer ends of said vanes to said ring at an angle on the side from which the flange projects. 25

In testimony whereof I affix my signature.

ELISA M. SOUVIELLE.
